No. 802,110.

PATENTED OCT. 17, 1905.

J. S. PETERMAN.

DAMPER.

APPLICATION FILED DEC. 30, 1904.

UNITED STATES PATENT OFFICE.

JOSEPH S. PETERMAN, OF PHILADELPHIA, PENNSYLVANIA, ASSIGNOR OF ONE-HALF TO HOWARD L. RAHN, OF PHILADELPHIA, PENNSYLVANIA.

DAMPER.

No. 802,110.

Specification of Letters Patent.

Patented Oct. 17, 1905.

Application filed December 30, 1904. Serial No. 238,883.

To all whom it may concern:

Be it known that I, JOSEPH S. PETERMAN, a citizen of the United States, residing in the city and county of Philadelphia, State of Pennsylvania, have invented a new and useful Damper, of which the following is a specification.

My invention consists of a damper for a stove, furnace, &c., adapted to work sensitively and possess simplicity, compactness, strength, and durability, and other advantages are presented, as will be hereinafter described, the novel features being pointed out in the claims.

15 Figure 1 represents a front elevation of a damper embodying my invention. Fig. 2 represents a vertical section thereof on line *xx*, Fig. 1. Fig. 3 represents a perspective view of a detached portion. Fig. 4 represents 20 a section of a portion on line *yy*, Fig. 1. Fig. 5 represents a side elevation of the device on a reduced scale and shown in operative position.

Similar numerals of reference indicate 25 corresponding parts in the figures.

Referring to the drawings, 1 designates a collar capable of being attached to the branch 2 of a smoke pipe or flue 3 of a furnace, stove, &c., the fire of which is regulated by my device. On the outer end of the collar is the in-turned flange 4, in the upper portion of which at opposite places are the recesses 5, the metal or material of which is punched outwardly, forming the lips or fulcra 6 for the damper 7, 30 the latter consisting of a plate of suitable metal or material, which is adapted to abut against the inner face of the flange 4, thus closing the damper or swing inwardly therefrom, as shown by the arrow, Fig. 2, thus 35 opening the damper and admitting air into the pipe 3 for evident purposes.

The plate of which the damper is constructed has a horizontally-extending crimp 8, forming an offset, the terminals of which have recesses 9 therein, the upper wall 10 of which projects outwardly, so as to overlap the adjacent portion of the flange 4 of the collar 1, the bottom of said wall presenting a flat edge 11, which I denominate the "pivots" of the damper, the same resting freely on the lips 6, whereby the damper is adapted to oscillate with sensitiveness owing to the comparatively small frictional contact of said lips and pivots. It will also be seen that in assembling the device

a recess 9 in the damper-plate is presented to 55 a recess 5 of the flange 4, when by moving the plate—say to the left—the part of the plate below the offset 8 may enter the collar 1 behind said flange 4, while the part of the same above said offset is in front of or outside of 60 said flange, and the left-hand pivot is rested on the contiguous lip 6. Owing to the play afforded by the recesses 5 and 9, the plate may be moved to the right, when the pivot thereat may be seated on the lip 6 beneath it, and 65 thus the damper is properly hung and supported and adapted to operate, as above stated.

Rising from the top of the damper-plate and secured thereto is the screw-rod 12, on which are the separate weights 13 and 14, which may 70 be screwed up and down so as to adjust the balance of the plate with nicety for adjusting the damper to a predetermined pressure of air on the exterior of the lower portion of the damper, so that the damper may be opened 75 and closed relatively to the condition of the fire, and thus preserve an equable condition of the latter. It will be also seen that the plate has its pivots integral therewith, the collar having its fulcra or bearings for said 80 pivots also integral with the flange thereof, thus reducing the expense of manufacture, while also rendering the device simple in construction, while the offset 8 permits the damper-plate 7 to be partly outside and partly 85 inside of the flange 4, thus exposing the larger surface of said plate to the action of the pressure of the atmosphere and assisting to render the damper sensitive to action under 90 all conditions of the fire in the stove, furnace, &c.

Various changes may be made in the details of construction shown without departing from the general spirit of my invention, and I do not, therefore, desire to be limited in each case 95 to the same.

Having thus described my invention, what I claim as new, and desire to secure by Letters Patent, is—

1. In a damper, a flue, a movable damper-plate, said plate having recesses in the edge thereof, the upper walls of said recesses forming pivots, a flange on a member of said flue, said flange having recesses in the edge thereof, and lips on said flange adjacent to the recesses thereof, said pivots being freely supported on said lips.

2. In a damper, a movable damper-plate,

the same having recesses therein, the upper walls thereof forming the pivots of said plate, a collar, a flange on said collar, said flange having recesses therein, and lips on said flange adjacent to the recesses thereof, said pivots being freely supported on said lips.

3. In a damper, a collar, a movable plate having an offset forming surfaces of different vertical planes, and lips integral with said

collar, said offset plate and collar each having 10 recesses therein, the recesses of said plate being adapted to enter those of said offset and the upper walls of the recesses of said plate being seated on said lips.

JOSEPH S. PETERMAN.
